UNITED STATES PATENT OFFICE.

JAMES F. McELROY, OF ALBANY, NEW YORK; SUSIE H. McELROY, EXECUTRIX OF SAID JAMES F. McELROY, DECEASED, ASSIGNOR TO CONSOLIDATED CAR-HEATING COMPANY, A CORPORATION OF WEST VIRGINIA.

ELECTRICAL PLUG AND SOCKET.

1,228,577.

Specification of Letters Patent.

Patented June 5, 1917.

Application filed February 27, 1912. Serial No. 690,282.

To all whom it may concern:

Be it known that I, JAMES F. McELROY, a citizen of the United States, residing at Albany, county of Albany, State of New York, have invented certain new and useful Improvements in Electrical Plugs and Sockets, the following being a full, clear, and exact disclosure of the one form of my invention which I at present deem preferable.

For a detailed description of the present form of my invention, reference may be had to the following specification and to the accompanying drawing, which illustrates my invention.

Figure 1 is an elevation, partly in section, of the plug;

Fig. 2 is a transverse section of Fig. 1;

Fig. 3 is a front elevation and

Fig. 4 is a side elevation of the socket-casing without the plug;

Fig. 5 is a front elevation and

Fig. 6 a side elevation of the socket-casing with the plug inserted;

Fig. 7 is a horizontal section of the socket and

Fig. 8 a vertical section of the same with the plug in place;

Fig. 9 shows detached details.

My invention relates to a plug and socket for temporary connection of an electrical device such as an electric heater to a supply circuit of high potential. The entering portion of the plug, shown at 20 in Figs. 1 and 2, is rectangular in cross section with a rib 21 along one edge (see also Fig. 7) which prevents the entry of the plug in any position except the right one. The handle portion 23 of the plug is round in cross section, except in the middle where it is oval.

The body of the plug is made of insulating material and it divides transversely on the line α . Near the center of the entering part two metallic contact blocks 22 are inset, one on each of the opposite faces, and each block having its outer surface grooved transversely while the two are insulated by the body of the plug. The blocks or contact pieces 22 are smaller in area than the respective faces of the plug in which the blocks are inserted, the blocks being thereby surrounded by an insulating surface extending to the tip or extremity of the plug. Between the two separable halves of the

plug is a cavity forming a connection-chamber in the top wall of which are two recesses each containing a screw-block connected by a rod 25 with one of the contact blocks 22. The upper half also has embedded therein two nuts 24, one of which projects out through the side of the plug to serve as a locking lug in a manner hereinafter described. Each of the nuts 24 receives a screw 27 which extend longitudinally of the plug, passing up from beneath through a perforated projection or offset on the inside of the metallic shell 28 which incloses the handle end of the plug. The screws 27 secure together the separable halves of the plug and also permit the lower half, which is bored axially to receive the conductor-cord 29, to be slipped down along the cord to give access to the connection-chamber 26 wherein the terminals of the wires in the conductor-cord may be secured to the respective screw-blocks mentioned above.

The socket is shown in detail in Figs. 7 and 8. It includes a cubical box 30 of insulating material with a slot on its under side, and this slot has a rectangular outline fitting closely the rectangular outline in cross section of the entering portion of the plug. The exact shape of the box 30 is not material, so long as its side walls at the ends of the slot fit the entering edges of the plug, to form a close fit therewith. The said entering portion of the plug is also of a width, in its wider dimension, equal to the interior width of the socket box 30 and of such length that, when fully entered, its tip will abut against the top wall of the box. By this arrangement the entering portion of the plug, when fully inserted will form a complete wall or partition across the interior space within the box, leaving each contact block 22 in a separate chamber formed by the said partition. The interior width of the box in a direction transverse to, or at right angles to the thickness of the plug is greater than such thickness of the plug in order to provide the distinct chambers on either side of the plug when it is in place in the socket. In the two upper corners of the box 30 are two blocks of metal 32 screwed to the respective side-walls of the box, but exposed at the rear (as shown in Fig. 7) through two openings in the rear wall of the

box, where the circuit wires are attached to the respective blocks 32. Each block 32 carries a contact spring 31 bent at its outer or free end into a curved form to fit the 5 grooved face of one of the contact blocks 22 on the plug. The said contact blocks 22, it will be observed, stand just inside of the slot through which the plug enters box 30, the extremity of the plug passing beyond the 10 ends of the springs 31 to fit against the top wall of the box as I have heretofore mentioned. By this means any arc that may occur, on the withdrawal of the plug, between either of the blocks 22 and its corresponding 15 spring 31, will not be able to pass over the extremity of the plug to cause a short-circuit, but will be broken by the passing of the blocks 22 and by the surface of the plug which follows the blocks into the slot. The 20 arcing distance from the lower extremities of springs 31 to the adjacent edge of the slot is far shorter than the arcing distance from one spring 31 around the extremity of the plug to the opposite spring 31, so that an 25 arc which might form over the shorter distance would be extinguished before it had an opportunity to expand to a length that could bridge the longer distance.

The socket thus described I preferably 30 close in a metallic casing 40 of similar shape which is provided with a cover 41 hinged on rod 43 and normally held, by spring 42, in the position shown in Figs. 3 and 4, to cover over and close the slot through which the 35 plug enters the socket. It is provided with out-turned lips 44 by which it may be grasped and turned into the position shown in Figs. 5 and 6 to permit the insertion of the plug in the socket. Then a latch 45 on 40 the inside of the cover 41 will snap under the locking lug 24 which I have heretofore mentioned and thereby lock the plug in position in the socket. The latch will be maintained in position by spring 42 and can be 45 readily released by drawing the cover 41 aside by means of the lips 44.

What I claim as new and desire to secure by Letters Patent is:

1. The combination with a socket member 50 having an internal cavity provided with spaced apart internal contacts, a plug provided with a small contact block on each face of its entering portion, the entering portion of the plug being of such dimensions as to divide said cavity into isolated, 55 independent chambers, one contact of the socket and the corresponding contact of the plug being located in each chamber, the entrance opening of the cavity being smaller than the cavity to form a tight fit with the plug.

2. The combination with a socket member 60 having an internal cavity provided with spaced apart internal contacts, a plug provided with a small contact plug on each

face of its entering portion, said entering portion being of a width equal to the internal width of a cavity and of a thickness less than the transverse width of the cavity, whereby the entering of the plug into the cavity will divide the latter, into isolated, 70 independent chambers, one contact of the socket and the corresponding contact of the plug being located in each chamber, the entrance opening of the cavity being smaller than the cavity to form a tight fit with the plug. 75

3. The combination with a socket member having an internal cavity provided with spaced apart internal contacts, a plug provided with a small contact block in each face of its entering portion, said entering portion being of a width and depth equal to the internal width and depth of the cavity, and of a thickness less than the trans- 80 verse width of the cavity, whereby the entry of the plug into the cavity will divide the same into isolated, independent chambers, one contact of the socket and the corresponding contact of the plug being located in each chamber, the entrance opening of the cavity being smaller than the cavity to form a tight fit with the plug. 85

4. A plug of insulating material formed in two parts separable on a line across the 90 length of the plug, the meeting edges of the two parts being recessed to form a connection chamber, contact blocks on opposite faces of the entering part of the plug with a conductor extending from each block to 95 the said chamber, a nut embedded in one of the two parts, and a screw passing longitudinally through the other part, the last mentioned part being longitudinally perforated to receive the conductor cord. 100

5. A plug of insulating material formed in two parts separable on a line across the length of the plug, the entering portion being of insulating material with a nut embedded therein, and the handle portion being also of insulating material and provided with an internal offset portion, a metal shell having a complementary internal offset portion, a screw passing through the offset portion of the metallic shell and the 110 handle portion and entering the said nut. 115

6. A plug socket comprising a receptacle of insulating material provided with an internal cavity, one wall of which is provided with a narrow slot of less width than said 120 cavity and equal to the interior length of the cavity, said slot being positioned to cause the entering plug to engage the wall opposite the slot, whereby the interior space of the socket may be divided into two oppositely disposed parallel non-communicating distinct chambers. 125

7. A plug-socket in the form of a closed receptacle of insulating material provided with an internal cavity and having on one 130

side a narrow guiding slot for the entry of the plug and spring contacts secured at points opposite said slot and adjacent the top of the casing and projecting to points 5 of contact adjacent to the entrance of the slot.

8. The combination with a plug-socket in the form of a closed receptacle provided with an internal cavity and having a narrow slot on one side of a length equal to the 10 interior width of the socket, and socket-contacts adjacent to said slot, of a plug having its entering portion of the same width and thickness as said slot and contacts on its opposite faces located back from the top thereof to engage the socket-contacts, whereby the entering plug will divide the interior of the socket into two distinct oppositely disposed parallel non-communicating chambers containing respectively the contacts for 15 the two sides of the circuit.
9. The combination with a socket, of a plug formed in two sections, a nut embedded in and projecting laterally from the 20 entering section of the plug, a screw in the handle section of the plug engaging the nut to hold the plug sections assembled, a casing inclosing the socket, and means carried by the casing for engaging the projecting 25 portion of the nut to hold the plug in engagement with the socket.
10. The combination with a socket of a

35 plug formed in two sections, a nut embedded in and projecting laterally from the entering section of the plug, a screw in the handle section of the plug engaging the nut to hold the sections assembled, a casing inclosing the socket and provided with a hinged cover, and a latch carried by the 40 cover for engaging the projecting portion of the nut to hold the plug in engagement with the socket.

11. In combination a socket having an internal longitudinally extending groove, contacts disposed in opposite portions of said 45 socket, and a plug having an entering portion provided with a rib that engages the socket, said entering portion having two of its opposite sides engaging similar sides of the socket and the free end of the entering portion abutting the closed end of the socket, said plug being of such dimensions 50 as to form two oppositely disposed independent contact chambers in the socket, and contacts carried by the entering portion of the plug and engaging the contacts of the 55 socket.

In witness whereof I have hereunto set my hand, before two subscribing witnesses, this 24th day of February, 1912.

JAMES F. McELROY.
